UNITED STATES PATENT OFFICE

JOSEPH RAH, OF CHICAGO, ILLINOIS, ASSIGNOR TO THE DELTA-STAR ELECTRIC COMPANY, OF CHICAGO, ILLINOIS, A CORPORATION OF ILLINOIS

INSULATING JOINT

Application filed February 8, 1930. Serial No. 426,813.

This invention relates to cable joints, and has particularly to do with a novel and improved type of insulating joint for underground cables, with the object of sectionalizing the exterior sheath of a cable in an oil-tight manner and in insulated relation.

It is one of the objects of the present invention to provide an insulating joint for metal sheathed cables which joint is so arranged that it may be applied to any part of a cable, including even a curved or bent portion thereof.

It is a further object of the present invention to provide an insulating sleeve for a cable joint wherein the mechanical connection between the insulation and the metallic parts is such as to place the insulation primarily under compressive stress as distinguished from bending or tension stresses.

There are other objects and features which will appear as the description progresses.

The invention will now be described in connection with the accompanying two sheets of drawings, in which:

Figure 1 shows the cross section of an oil-tight insulating joint according to one way of carrying the invention out in practice;

Fig. 2 illustrates a sectional view taken on line 2-2 in Figure 1; and

Figure 3 illustrates a modification of an oil-tight insulating joint having adjustable and mechanically removable means for attaching the lead sheath to the insulating casing.

Like parts in the drawings are indicated by like reference numerals.

Referring now to the drawings, Figure 1 and Figure 2, numeral 1 designates a tubular insulating casing for exteriorly embracing a cable. Mechanically attached at both ends of this insulating casing are the clamp members 2 and 3. Each of these clamp members consists, as is shown in Figure 2, of a number of sections 4, 5 and 6, provided with peripheral extensions 7-8, 9-10, 11-12, respectively, which are assembled peripherally around and embracing the peripheral rounded protuberances 13 and 14 provided on the insulating casing 1. Interposed between the sections 4, 5, 6, of the clamping members and

the insulating casings, are layers 15 and 16 of lead or of other suitable material providing a cushion effect between and a firm grip of the clamp sections on the tubular insulating casing 1. The clamp sections are fastened to each other by means of bolts 17, 18 and 19, engaged by nuts 20, 21 and 22. Interposed between the nuts and the corresponding extensions of the clamp sections are the usual washers 23, 24 and 25. The clamp sections are provided with suitable circularly arranged threaded holes 26, 27, 28 and 29.

It will be understood, of course, that the number of clamp sections shown and disclosed above in connection with the manner of reducing the invention to practice as illustrated in Figures 1 and 2, is more or less arbitrary and intended to serve primarily the purpose of description and explanation. There may be more or less clamp sections provided, or these sections may be attached in a manner differing in detail from the manner illustrated, without altering the inventive idea of using sectional clamps mechanically attached to the insulating casing.

The advantages resulting from the use of such sectional clamps are obvious. The insulating casing is securely embraced by forces acting from a plurality of circumferentially symmetrical points, holding the insulating casing tight and without any danger of breakage. Prior constructions have disclosed a type of clamp permanently attached to an insulating casing by cementing or by moulding the metal fittings into the insulating material or the like.

The superiority of the instant case in which mechanically removable and adjustable sectional clamping means are used, over rigidly attached mounting chambers, as intimated above, will be readily appreciated. In case of the latter, strains and stresses imposed upon the structure will not be equalized at all, but will react upon the unit, and under certain conditions react to the detriment of the assembly. In the present structure, due to the sections of the clamps gripping the insulating body firmly from a plurality of peripherally symmetrical points, and due to

the cushion effect of the layer interposed between the clamp sections and the insulator, strains and stresses will be equalized and the assembly will adjust itself automatically to stresses imposed upon the same under ordinary conditions.

Continuing now the description of the invention, a wiping sleeve, such as 30 and 31, is attached to the clamp members 2 and 3, at both ends of the insulating casing 1, by means of cap screws 32—33, and 34—35, respectively, which are inserted into the corresponding threaded holes, such as 26, 27, 28 and 29, on the clamp members as shown in Figure 2. It is understood, of course, that there are four such cap screws for holding each of the wiping sleeves in engagement with the corresponding clamp sections. Gaskets 36 and 37 are interposed between the corresponding ends of the insulating casing 1 and the flanges of the corresponding wiping sleeve attached to it.

The cable is drawn through the assembly, with a section of its exterior lead sheath removed and the ends 38 and 39, respectively, of the wiping sleeve 30 and 31, are, in case of wiping sleeves having lead skirts, attached to the lead sheath of the cable at both sides of the assembly, by means of hammering, rolling, or pressing, in the usual manner, joining the ends of the lead sheath to the corresponding wiping sleeve in oil-tight relation thereto. It is, of course, understood that rigid cast wiping sleeves may be employed in place of sleeves having lead skirts. No hammering, rolling or pressing will be necessary in such a case. The sleeve is simply attached exteriorly to the sheath, and a lead ring or sleeve is applied to the junction for sealing the same.

The oil-tight insulating joint, sectionalizing the lead sheath of the cable is now completely assembled and joined to the sheath of the cable in oil-tight relation. It will be appreciated that the construction as described, is of utmost simplicity in design and operation and at the same time reliable in use, having numerous novel features not found in prior devices of this kind.

A modification of the device just described, in which mechanically removable and adjustable means for securing the lead sheath of the cable in oil-tight relation to the two ends of the insulating body are provided in place of the wiping sleeve, is shown in Figure 3.

A cursory inspection of the drawing shown in Figure 3 will show that the same split, or sectional, clamp members are attached mechanically to the insulating casing as were described in connection with Figures 1 and 2. Accordingly, a detailed description of these clamping members will be omitted in the following explanations. Details in Figure 3 which correspond to Figures 1 and 2 are designated with like reference numer-

als, and the description of Figures 1 and 2 may be consulted for supplying information omitted here for the sake of avoiding unnecessary repetition of matter.

Referring now to Figure 3, the cable, entering the insulating joint at 40 and leaving the same at 65 is again stripped of its external lead sheath, and the ends 41 and 64 of the sheath are mechanically and adjustably joined to the insulating body 1 and in oil-tight relation thereto.

This is accomplished by means of attaching to each end of the insulating body 1 a sleeve member 44 and 56, respectively, having flanges 45 and 51 for attachment to the clamping members 2 and 3, by interposing gaskets 36 and 37, as was explained in connection with the wiping sleeves 30 and 31 in the structure described previously by referring to Figures 1 and 2. These sleeve members 44 and 56 are alike in structure and function, and only one will be fully explained for convenience of description, that is, the one attached at the lower end of the insulating body 1 and designated by numeral 44.

The lower circular portion 43 of this mechanical sleeve member is widened and provided with an internal thread 47 and with a circular interiorly projecting rim 57. The end 41 of the cable sheath is inserted into this rim portion, and securely fastened to it by means of the circular nut member 46 provided with a thread to engage the threaded part 47 of the sleeve extension 43. The end 48 of the nut member 46 is rounded and conforms to the shape of the rim 57 to provide a secure grip and tight fit for the end of the cable sheath 41.

The other end 64 of the lead sheath is secured in exactly the same manner, by means of the nut member 63, fastening the same to the rim 58 of the sleeve 56, which in turn is fastened to the corresponding end of the insulating casing 1 by means of flange 51 provided with holes 52 and 53 for taking the cap screws 32 and 33.

It is believed that the above description of the modification shown in Figure 3 will suffice for fully disclosing the inventive features; and, in summing up the functions and advantages of the device over devices disclosed prior to my invention, it may be said, and will be appreciated, that I have provided a novel, oil-tight insulating joint for sectionalizing the external sheath of underground cable for the purpose of reducing induction and thereby reducing power loss, incorporating numerous novel structural and functional features which represent an advance in the art in many respects.

Accordingly, I desire to secure Letters Patent for my invention which is particularly defined in the following claims:

I claim:

1. A device for interrupting the conduc-

- tive continuity of the exterior sheath of an underground cable while maintaining the continuity of the cable insulator and of the cable conductors, comprising a unitary tubular insulating casing for receiving said cable, an enlargement near each end of said casing and integral therewith, sectional clamping means, internal grooves in said clamping means for embracing said enlargements on said casing, packing means in said grooves for cushioning said clamping means on said enlargements, a gasket positioned at each end of said casing, tubular sleeve means engaging each of said gaskets at each end of said casing, the inner diameter of said sleeve means corresponding substantially to the inner diameter of said casing, means for removably attaching said sleeve means to said clamping means, a laterally extending enlargement on each of said sleeve means, an annular groove in said laterally extending enlargement for receiving the sheath of said cable at the end of each sleeve means, an internal thread in said radially extending enlargement on each sleeve, and a tubular screw for fastening the sheath of said cable to the enlargement on each sleeve and in oil-tight relation therewith, said tubular screw having a rounded head portion for clamping said sheath in the annular groove in said enlargement on the sleeve and a cylindrical portion at the end thereof for engaging the outer diameter of said sheath, said cylindrical portion and said rounded head portion of said tubular screw being separated by an internal annular notch in said screw.
2. A device for interrupting the electrical continuity of a metallic sheath of a continuous run of cable, said device comprising a tubular insulator adapted to be slipped over a cable and of an internal diameter greater than the external diameter of a cable over which it is to be slipped, whereby the insulator may be slid over bends in the cable, and a pair of sleeve means connected to the opposite ends of the insulator and adapted to constitute a portion of a mechanical fluid-tight connection between each end of the insulator and the adjacent sheath portion of a cable, the connection between each of the sleeve means and the tubular insulator including a flanged split clamp to which the sleeve is connected and a ball and socket joint between the insulator and each of the split clamps to permit a slight angular adjusting motion of each of the sleeve means with respect to the insulator, whereby the device may be located along a curved portion of a cable while maintaining each of the sleeves directed substantially axially of the adjacent cable portion.
3. A device for interrupting the electrical continuity of a metallic sheath of a continuous run of cable, said device comprising a tubular insulator adapted to be slipped over
- a cable and of an internal diameter greater than the external diameter of a cable over which it is to be slipped, whereby the insulator may be slid over bends in the cable, and a pair of sleeve means connected to the opposite ends of the insulator and adapted to constitute a portion of a mechanical fluid-tight connection between each end of the insulator and the adjacent sheath portion of a cable, the connection between each of the sleeve means and the tubular insulator including a flanged split clamp to which the sleeve is connected and a ball and socket joint between the insulator and each of the split clamps to permit a slight angular adjusting motion of each of the sleeve means with respect to the insulator, whereby the device may be located along a curved portion of a cable while maintaining each of the sleeves directed substantially axially of the adjacent cable portion, the outer end of each sleeve including a shoulder against which the end of the sheath bears, and a clamping member removably secured to the end of each sleeve and clamping the end of the sheath to said shoulder to form a liquid-tight seal therewith.
4. A device for interrupting the electrical continuity of a metallic sheath of a continuous run of cable, said device comprising a tubular insulator adapted to be slipped over a cable and of an internal diameter greater than the external diameter of a cable over which it is to be slipped, whereby the insulator may be slid over bends in the cable, and a pair of sleeve means connected to the opposite ends of the insulator and adapted to constitute a portion of a mechanical fluid-tight connection between each end of the insulator and the adjacent sheath portion of a cable, the connection between each of the sleeve means and the tubular insulator including a flanged split clamp to which the sleeve is connected and a ball and socket joint between the insulator and each of the split clamps to permit a slight angular adjusting motion of each of the sleeve means with respect to the insulator, whereby the device may be located along a curved portion of a cable while maintaining each of the sleeves directed substantially axially of the adjacent cable portion, the outer end of each sleeve including a shoulder against which the end of the sheath bears, and a clamping member removably secured to the end of each sleeve and clamping the end of the sheath to said shoulder to form a liquid-tight seal therewith.
5. In a device of the class described, for sectionally interrupting the conductive continuity of the exterior sheath of a cable, a flanged tubular sleeve, a radially projecting and axially extending enlargement on the end of said sleeve, an annular groove in said end

largement, an internal thread in said enlargement, a tubular screw for engaging said thread, the head of said tubular screw being annularly rounded to clamp said cable sheath against said annular groove, the other end of said tubular screw being cylindrical for engaging the outer diameter of said cable, and an intermediate annular notch internally of said tubular screw between said cylindrical portion and said annularly rounded head portion thereof.

6. A device of the class described, for sectionally interrupting the conductive continuity of the external sheath of a cable, comprising a unitary tubular insulating casing, the inside of said casing being substantially cylindrical, circular enlargements on said casing and integral therewith, one disposed near each end of said casing, a sectional clamp removably secured to each of said circular enlargements, a gasket positioned at each end of said casing, a tubular sleeve for each end of said casing, said sleeve having a laterally extending flange and an axially extending tubular portion, said flange of said sleeve being positioned in engagement with said gasket at the end of said casing to provide an oil tight joint between said sleeve and said casing, screw means axially extending through said flange on each sleeve and engaging threaded holes in said clamping means secured to said casing for securing said sleeve in position, part of the axially extending sleeve portion being cylindrical and its inner diameter corresponding substantially to the inner diameter of said casing, the end of said sleeve being of substantially L-shaped cross section with an annular groove at the base thereof for receiving the end of said cable sheath, and a tubular screw cooperating with said sleeve for clamping said sheath in engagement with said annular groove in said sleeve.

7. A device of the class described, for sectionally interrupting the conductive continuity of the external sheath of a cable, comprising a unitary tubular insulating casing, the inside of said casing being substantially cylindrical, circular enlargements on said casing and integral therewith, one disposed near each end of said casing, a sectional clamp removably and yieldably secured to each of said circular enlargements, a gasket positioned at each end of said casing, a tubular sleeve for each end of said casing, said sleeve having a laterally extending flange and an axially extending tubular portion, said flange of said sleeve being positioned in engagement with said gasket at the end of said casing to provide an oil tight joint between said sleeve and said casing, screw means axially extending through said flange on each sleeve and engaging threaded holes in said clamping means secured to said casing for securing said sleeve in position, part of the axially extend-

ing sleeve portion being cylindrical and its inner diameter corresponding substantially to the inner diameter of said casing, the end of said sleeve being of substantially L-shape cross section with an annular groove at the base thereof for receiving the end of said cable sheath, and a tubular screw cooperating with said sleeve for clamping said sheath in engagement with said annular groove in said sleeve, said tubular screw having an annularly rounded head portion for engaging said sheath and for clamping said sheath against said annular groove and a substantially cylindrical guide portion for circumferentially engaging the free sheath of said cable, and an annular intermediate internal groove between said head portion and said guide portion.

In witness whereof, I hereunto subscribe my name this 5th day of February, 1930.

JOSEPH RAH.
